UNIFRAME SHIP'S WINDOW

Waldo L. Kraemer, Brooklyn, N. Y., assignor to
 Kearfott Engineering Company, Inc., a corpora-
 tion of New York

Application March 29, 1930. Serial No. 439,870

8 Claims. (Cl. 114—177)

My invention relates to sheltered deck windows for ship constructions and in particular to a unitary window having a shutter operable for closing the window opening.

5 In certain ships, it is desirable to have shutters in addition to the window-panes for closing the window opening and enclosing the window-pane. The common practice in constructing ships is to install the windows in a series, the 10 operating mechanism of the series of windows being enclosed with framework common to all of the windows.

Such constructions are expensive to install and have the objectionable feature that pockets are 15 formed beneath the windows and enclose the operating mechanism thereof, which pockets are inaccessible and cannot therefore be reached for painting or other treating to insure protection from the elements. Consequently, the surfaces 20 of these inaccessible pockets are subject to relatively rapid deterioration since water entering between the window-pane and the frame is caught in these pockets and the elimination of such inaccessible pockets is, therefore, desirable. 25 Also, complicated operating mechanism is necessary for the operation of the shutters and window-pane and this mechanism is not readily accessible for repair.

By my invention, I am enabled to eliminate 30 the formation of such objectionable pockets and to provide a construction in which the operating mechanism of the window-pane and shutter is simple, inexpensive and readily accessible for repair. I employ a construction in which each 35 window is a unitary structure. In this unitary structure, the window-pane operating mechanism and the shutter operating mechanism are spaced and supported by a single frame.

An advantage of my construction is the fact 40 that every portion of the window is accessible for painting and repair.

Specifically, I provide a construction which 45 comprises a single frame member. The frame member is provided with an outwardly extending flange which may be secured to the side of the ship by bolts or other suitable securing means. Secured to the inner surface of the sides and upper cross piece of the frame member, there are two parallel guideways, a window-pane 50 guideway and a guard plate guideway. The guard plate guideway is substantially in line with the outwardly extending flange on the frame member, the window-pane guideways being spaced inwardly from the guard plate guideways. A cross piece at substantially the center

of the frame member supports a thrust bearing in which the upper end of a vertical screw shaft is journaled, the lower end being journaled in a bearing supported by the lower cross member of the frame. On the screw shaft there is a nut 60 which is moved longitudinally of the screw shaft when the screw shaft is rotated. The nut engages a member secured to the lower edge of the window-pane and raises or lowers the window-pane in the guideway upon rotation of the screw shaft. The screw shaft may be rotated by a handle secured on a shaft extending through the aforementioned central cross member, the shaft upon which the handle is journaled being mechanically connected to the screw shaft to transmit rotational movement thereto. This window-pane traversing means is common to the guard plate, means being provided however to disconnect the guard plate from the traversing means so that the window-pane may be raised or lowered independently of the guard plate. A shield, supported by the central cross member which supports the aforementioned thrust bearing, in conjunction with the frame member, encases the window-pane traversing mechanism. Thus, the 70 window may be assembled and secured to the side of the ship as a unit.

Other features and advantages will be apparent from the following description of one embodiment of my invention taken in connection with the accompanying drawing in which:

Fig. 1 is an elevation of a window constructed in accordance with my invention;

Fig. 2 is a sectional plan of the same taken on the line 2—2 of Fig. 1;

Fig. 3 is a longitudinal section taken on line 3—3 of Fig. 1; and

Fig. 4 is a fragmentary sectional plan taken on the line 4—4 of Fig. 3.

The window shown in the drawing comprises 95 a frame 1 constructed from angle members of L-shape in cross section, one of the flanges 2 of the L-section members extending outwardly with respect to the frame. This outwardly extending flange 2 is adapted to be secured to the 100 side of the ship in which the window is placed, any suitable securing means, such as bolts, being used for the purpose. To the inner surface of the side and upper cross member of the frame, there is secured two guideways, a window-pane 105 guideway 3 and a guard plate guideway 4.

The guard plate guideway 4 is U-shape in cross section and is secured to the frame member so that the outer surface of one leg of the U is in alignment with the outer surface of the 110

outwardly extending flange 2 of the frame member. The window-pane guideway 3 is spaced inwardly from the guard plate guideway and the guideways are maintained in spaced relation by 5 a spacing member 5.

The window-pane guideway is also U-shaped in cross section but has a flange 6 lying in a plane of the web of the U and forming an extension thereof. The flange 6 of the window-pane guideway is secured to the frame 1 by means of bolts 7. This guideway is constructed from a single sheet of metal, the flange 6 being formed thereon by bending the metal back upon itself. The guideway is lined with some suitable material, such as felt. In the window-pane guideway, there is slidably mounted a frameless glass window-pane 8 and in the guard plate guideway there is slidably mounted a steel guard plate 9.

20 The window-pane is raised and lowered in the window-pane guideway by window-pane traversing means. The window-pane traversing means comprise a vertical screw shaft 10. The upper end of the screw shaft is journaled in a thrust bearing 11 which is supported by a cross member 12 which extends between the sides of the frame member substantially at the center of the frame. The upper end of the screw shaft is maintained in the thrust bearing by a nut 13 threaded on the end of the screw shaft. At the lower end, the screw shaft is journaled in a bearing 14 which is supported by the lower cross member of the frame 1. On the screw shaft, there is a nut 15 having internal threads corresponding to the threads of the screw shaft. The nut 15 is provided with an integral collar 16 at its lower end and with an integral radial projection 17 intermediate its ends. The collar 16 on the nut is engaged by integral projections 18 formed on a member 19 and the integral projection 17 on the nut engages an opening 20 in the member 19 so that movement of the nut longitudinally of the shaft moves the member 19 therewith. The member 19 is secured to a clamp member 21 in which the lower edge of the window-pane 8 is secured, a packing strip 22 being interposed between the metal of the clamp member and the window-pane. Thus, rotation of the screw shaft moves the nut longitudinally thereof 45 and raises or lowers the window-pane depending upon the direction of rotation of the screw shaft. On the lower edge of a frame member 23 surrounding the guard plate there are two projections 24 to which members 25 are hinged. These 50 members 25 are spaced apart such that when moved into position parallel to each other they straddle the projections 18 on the member 19 secured to the clamp member 21 of the window-pane 8. In this position, the members 25 are 55 also engaged by the collar 16 on the nut so that the guard plate is raised and lowered with the window-pane. If it is desired to raise and lower the window-pane independently of the guard plate, the hinged members are swung about the hinge connection to a position in which they are not engaged by the nut 15. The screw shaft 10 may be rotated by a handle 26 which is secured to the end of a short shaft 27. On the opposite end of the short shaft there 60 is a gear 28 which meshes with a gear 29 on the screw shaft. Thus, rotational movement of the handle 26 is transmitted to the screw shaft to raise or lower the window-pane in the guideways.

A plate 30 is adapted to cover the opening between the window-pane guideway and the outer

edge of the frame when the guard plate is not in use. The plate 30 is hinged secured to a bracket 31 and extends across the frame member 1. The plate is pivoted so that its normal position is that in which it covers the opening between the window-pane guideway and the outer edge of the frame as shown in Figure 3. 80

The window-pane traversing means is enclosed by a shield. The shield consists of two parts, an upper part 32 which is bent over the top of the window-pane traversing means and a lower part 33 which extends downwardly in front of the frame member, the sides thereof being bent inwardly toward the frame member. The shield is removably supported by the cross member 12 which supports the thrust bearing for the screw shaft and an L-shape member 33' secured to the lower end of the frame member. At the lower portion of the shield, there is a sliding door 34 through which access may be had to the hinged members 25. In this way, these hinged members may be manipulated to engage the nut of the window-pane traversing means or vice versa as desired. The guard plate 9 is, of course, used only during storms in which the window-pane is liable to be broken. The shield and the frame are so connected that water entering between the shield and the frame cannot escape onto the deck. 95

From the above description of the illustrated embodiment of my invention, it will be apparent that I have produced a unitary shelter deck window which may be easily and readily installed or replaced and which when in position is completely accessible for repair. 100

It is obvious that various changes may be made in the illustrated embodiment of my invention above particularly described by those skilled in the art within the principle and scope of my invention as expressed in the appended 115 claims.

I claim:

1. A unitary shelter deck window comprising a frame member of L-shape in cross section enclosing and supporting window-pane guideways, guard plate guideways parallel to the window-pane guideways, a window-pane slidably mounted in the window-pane guideways, a guard plate for the window-pane slidably mounted in the guard plate guideways, and traversing means common to the window-pane and the guard plate, and a shield secured to the frame member enclosing the traversing means and the window-pane and guard plate in the open position thereof. 120

2. A unitary shelter deck window comprising a frame member of L-shape in cross section enclosing and supporting a window-pane and a guard plate guideway, a window-pane slidably mounted in the window-pane guideway, a guard plate for the window-pane slidably mounted in the guard plate guideway and traversing means common to the window-pane and the guard plate including means for releasing the guard plate from the traversing means, and a shield secured to the frame member enclosing the traversing means. 130

3. An interchangeable unitary shelter deck window comprising a frame member having an outwardly extending flange adapted to be secured to the side of a ship, the frame member enclosing window-pane guideways, guard plate guideways parallel to said window-pane guideways and spaced therefrom, a frameless window-pane slidably mounted in the guideways, a guard plate for the window-pane slidably mounted in 145

the guard plate guideways, and traversing means common to the window-pane and the guard plate, and a shield secured to the frame member and enclosing the traversing means and the 5 window-pane and guard plate in the open position thereof.

4. An interchangeable unitary shelter deck window comprising a frame member substantially twice the length of the window opening 10 having an outwardly extending flange adapted to be secured to the side of a ship, the frame member encasing channel-shaped window-pane guideways secured to the sides and top of the frame, channel-shaped guard plate guideways 15 secured to the sides of said frame member parallel to said window-pane guideways and spaced therefrom, a frameless window-pane slidably mounted in the window-pane guideways, a guard plate slidably mounted in the guard plate guideways, window pane traversing means adapted 20 to engage the lower edge of the window-pane including a vertical shaft, a bearing for the lower end of said shaft secured to the frame member, a cross member at substantially the transverse 25 center of the frame member having an opening therein for the upper end of said shaft, and means for traversing said guard plate with said window-pane, and a shield extending from said cross member to the lower end of said frame 30 member and enclosing the window-pane traversing means.

5. In a window construction for a ship or other structure, a window pane slidable therein, a shutter spaced from said window pane, and means for raising said pane and shutter as a unit whereby to provide a double closure. 80

6. In a window construction for a ship or other structure, a frame therefor defining an opening, a transparent closure for the opening slidable in said frame, and an auxiliary closure for said opening for preventing damage to 85 said transparent closure, said closures being constructed for operation as a unit.

7. In a window construction for a ship or other structure, a frame therefor defining an opening, a pair of closures for the window opening 90 slidable in said frame, and means for raising one or both of said closures as a unit.

8. In a window construction for a ship or other structure, spaced guide rails attached to said frame, a pane of glass slidable in one 95 of said rails, a shutter slidable in the other of said rails, operating mechanism for lowering and raising said pane, and a bracket member attached to said shutter and provided with foldable arms adapted to seat on said operating 100 mechanism for permitting raising of said shutter with said pane when the operating mechanism is being actuated.
